UNITED STATES PATENT OFFICE

91,630

DESIGN FOR A SEAL

Samuel Klein, New York, and David R. Kasanof,
Brooklyn, N. Y.; said Kasanof assignor to said
Klein

Application December 24, 1930, Serial No. 38,113

Term of patent 14 years

To all whom it may concern:

Be it known that we, SAMUEL KLEIN and DAVID R. KASANOF, citizens of the United States and residents, respectively, of the city, county, and State of New York, and of Brooklyn, county of Kings, and State of New York, have invented a new, original, and ornamental Design for a Seal, of which the following is a specification, reference being had to the accompanying drawing, forming part thereof.

This application is a continuation in part of my application Serial No. D—35,260, filed April 15, 1930.

We claim—

The ornamental design for a seal substantially as shown.

SAMUEL KLEIN.
DAVID R. KASANOF.
